UNITED STATES PATENT OFFICE

FRED SWOYER, OF SILVER GROVE, AND THOMAS J. BRYANT, OF COVINGTON, KENTUCKY

NAIL AND SPIKE EXTRACTOR

Application filed May 1, 1930. Serial No. 449,032.

The invention relates to a nail and spike extractor.

The object of the present invention is to improve the construction of nail and spike extractors and to provide a simple, practical and efficient nail and spike extractor of strong, durable and comparatively inexpensive construction equipped with a plurality of nail and spike extracting claws adapted 10 to successively operate on a nail or spike and coact with a single fulcrum of the extractor and obviate the necessity of employing a so-called heel or other means supplemental to a single fulcrum face for enabling the final 15 stages of the extraction of a long nail or spike to be completed.

A further object of the invention is to provide a nail and spike extractor equipped with a relatively short outer claw adapted to enable great leverage to be exerted on a nail 20 or spike to start it so that the nail or spike, after being started, may be successively operated on by a relatively long claw and completely extracted by the same.

Another object of the invention is to arrange the relatively short and relatively long outer and inner claws so as to coact with a single fulcrum to obviate the necessity of providing a plurality of fulcrums and of 25 changing the fulcrum in changing from one claw to another. It is also an object of the invention to enable the said inner and outer claws to be arranged, when desired, so that the outer claw will bear against an intermediate portion of a long nail or spike while the same is being operated on by the relatively long claw, to avoid the severe bending of the nail or spike which results from the use of an ordinary single claw nail or spike extractor, so as to enable the nail or spike to be extracted at the expenditure of less power than when the nail or spike is severely bent and caused to frictionally engage and bind against one of the walls of the hole.

With these and other objects in view, the

invention consists in the construction and novel combination and arrangement of parts hereinafter described, illustrated in the accompanying drawings, and set forth in the claims hereto appended, it being understood 50 that various changes in the form, proportion, and minor details of construction, within the scope of the claims, may be resorted to without departing from the spirit of the invention or sacrificing any of the advantages 55 thereof.

In the accompanying drawings:

Figure 1 is a perspective view of a nail and spike extractor constructed in accordance 60 with this invention.

Fig. 2 is a side elevation of the same illustrating the operation of the outer claw, the latter being in its initial position in full lines and its final position in dotted lines.

Fig. 3 is a similar view illustrating the operation of the inner claw.

Fig. 4 is a side elevation showing a nail and spike extractor provided with three claws.

In the accompanying drawings, in which is illustrated the preferred embodiment of 70 the invention, the nail and spike extractor comprises in its construction a shank 1 consisting of a straight bar, preferably octagonal in cross section and having its curved outer end 2 curved forwardly and tapered as shown 75 to increase the thickness and strength of the bar at the outer end, so that the nail and spike extractor will be reinforced at the fulcrum formed by the curved outer end. The curved outer end 2 presents an outer convex face 3 which forms a single rolling fulcrum for the nail and spike extractor, which is provided with a relatively short outer claw 4 forming a prolongation of the curved end 2 of the shank and presenting an outer 85 face 5 which merges into the curved fulcrum face 3 of the end 2 of the shank. The nail and spike extractor is also provided at the curved end 2 with a relatively long claw 6 extending from the inner side of the curved 90

end 2 of the shank and arranged at an angle to the relatively short outer claw 4. Both claws are arranged to cooperate with the single rolling fulcrum of the shank and they are provided with similar openings 7 and 8 and have grooves 9 and 10 at their inner ends forming continuations of the nail and spike receiving openings of the claws and adapted to accommodate the heads of the nails and spikes. The openings 7 and 8 have side walls 5 which are parallel at the front faces of the claws, and the said walls are inclined and converge towards each other both longitudinally and laterally. The walls of the grooves 10 are curved and connect and merge into the inner ends of the side walls of the openings. 15

The claws are spaced one above the other and extend from the same rolling fulcrum and each successive claw has a longer leverage. Any number of claws may be employed, 20 and in Fig. 4 of the drawings is illustrated a nail and spike extractor having three claws 11, 12 and 13.

In operating the nail and spike extractor, 25 the relatively short outer claw is engaged with a nail or spike as illustrated in Fig. 2 of the drawings. The outer claw having a short leverage enables the operator with a short arm movement to start the extraction 30 of the nail or spike with less effort than with an ordinary single claw nail and spike extractor, which of necessity and for practicability must be constructed with a longer leverage than the short outer claw in order to 35 enable the operator of such single claw extractor to complete the extraction of short nails and spikes and also to make as full and as complete an extraction of long nails and spikes as possible. After the initial and 40 partial extraction of a nail or spike, as illustrated in dotted lines in Fig. 2 of the drawings, the nail is loosened in the hole and can then be further extracted with less effort than at the beginning of the operation. The operator 45 engages the head of the partially extracted nail or spike with the inner relatively long claw, as illustrated in Fig. 3 of the drawings. The relatively long inner claw, having a longer leverage than the outer claw, enables the 50 operator to complete the removal of the nail or spike with another short arm movement and without building up a fulcrum under the single rolling fulcrum formed by the curved end of the shank.

The nail and spike extractor may be constructed of any suitable size, and be provided 55 with any number of claws. The size of the devices will correspond to the character of the nails or spikes to be extracted. A much 60 lighter and shorter handle may be employed than is usually required by the ordinary single claw extractor, as the short claw will enable a nail or spike to be readily started with a short arm movement, and the initial stage 65 of the extraction of a heavy nail or spike may

be accomplished with less effort than is required by the ordinary single claw extractor, and after the nail or spike is loosened in the hole by the initial stage of the extraction, the intermediate and final stages of removal may 70 be effected with a longer and lighter claw than is possible with a single claw extractor because of the loosening of the nail or spike in the initial stage of the extraction. The relatively short outer claw of the nail and spike extractor during the final stages of the extraction will come in contact with the nail or spike as illustrated in Fig. 3 of the drawings, and eliminate some of the angular pull 75 of the relatively long claw and will assist 80 materially in the ease of the extraction.

What is claimed is:

1. A nail and spike extractor comprising a shank consisting of a bar having its outer end curved forwardly and presenting an outer curved end face forming a single rolling convex fulcrum, a relatively short outer claw forming a prolongation of the curved end of the shank and having an outer face merging into the curved face of the rolling fulcrum, and an inner relatively long claw extending from the curved end of the shank, said inner and outer claws having similar claw openings and both cooperating with the said single fulcrum to successively operate on a nail or spike, and the outer claw being adapted to cooperate with the inner claw and bear against an intermediate portion of the nail or spike while the same is being operated on by the inner claw during the final stages of extraction of said nail or spike to increase the ease of extraction. 90

2. A nail and spike extractor comprising a shank consisting of a bar having its outer end curved forwardly and presenting an outer curved end face forming a single rolling convex fulcrum, a relatively short outer claw forming a prolongation of the curved end of the shank and having an outer face merging into the curved face of the rolling fulcrum, and an inner relatively long claw extending from the curved end of the shank, said inner and outer claws having similar openings converging inwardly from parallel lines at the front faces of the claws and the latter being provided with central curved grooves forming extensions of the openings to accommodate the head of the nail or spike and the said outer claw being arranged to cooperate with the inner claw and bear against an intermediate portion of the nail or spike while the same is being operated on by the inner claw during the final stages of extraction of said nail or spike to increase the ease of extraction. 100

3. A nail and spike extractor comprising a shank consisting of a bar having its outer end curved forwardly and presenting an outer curved end face forming a single rolling convex fulcrum, a relatively short outer claw 110
